UNITED STATES PATENT OFFICE.

HAROLD W. SHONNARD, OF UPPER MONTCLAIR, NEW JERSEY, ASSIGNOR TO CRUCIBLE STEEL COMPANY OF AMERICA, OF PITTSBURGH, PENNSYLVANIA, A CORPORATION OF NEW JERSEY.

GYROSCOPE-SPINNING MECHANISM.

1,296,331.

Specification of Letters Patent.

Patented Mar. 4, 1919.

Application filed May 25, 1917. Serial No. 171,046.

To all whom it may concern:

Be it known that I, HAROLD W. SHONNARD, residing at Upper Montclair, in the county of Essex and State of New Jersey, 5 a citizen of the United States, have invented or discovered certain new and useful Improvements in Gyroscope-Spinning Mechanism, of which improvements the following is a specification.

10 My invention relates to gyroscopes, particularly such as are used in connection with steering mechanism for automobile torpedoes, and the object thereof is to provide a simple, effective and practical spring motor 15 mechanism for spinning the gyroscope rotor to a high velocity. A more specific object is to provide a spring motor mechanism for the purpose described, which, at the completion of the spin, is automatically moved out 20 of the range of the movement of the gyroscope.

In the accompanying sheets of drawings which form part of my specification, I have illustrated the preferred embodiment of my 25 invention. Figure 1 is a longitudinal central sectional view of the gyroscope and spinning mechanism, the plane of view being indicated by the line I—I, Fig. 2; Figs. 2 and 3 are, respectively, plan and right 30 end views thereof; and Fig. 4 a detail sectional view taken on the line IV—IV, Figs. 1 and 3.

While my invention is applicable to various forms and types of gyroscopes, it is 35 illustrated herein in connection with a gyroscope adapted to control the steering mechanism of an automobile torpedo. The gyroscope shown herein comprises a rotor 1, an inner gimbal 3 in which the rotor is mounted, and an outer gimbal 4 in which the inner gimbal is mounted and which, in turn, is pivotally mounted in suitable supports 5 and 6 secured to the housing or frame 7. As will be readily understood, the pivot 40 axis of the gimbal 4 is likewise the axis of the gyroscope. Any well known or preferred form of controlling mechanism may be associated with the gyroscope, that shown herein mounted on the frame 7 being the 45 same as is shown and described in my pending application, Serial No. 171,045, filed of even date herewith.

The spinning mechanism which I provide (and it is with such mechanism that my invention is primarily concerned) includes

a movably mounted spring motor and a driving member secured thereto and adapted to be associated with the gyroscope for spinning it, and with such mechanism there are associated means for winding the spring 60 motor, means effective upon the spinning of the gyroscope for moving the mechanism from spinning position, and means for returning the motor to spinning position.

In the practice of my invention the several stated elements may be variously constructed and variously arranged with relation to each other and to the gyroscope; however, they are preferably combined in a single unit which is movable laterally to 70 and from the gyroscope. To such end the unit is suitably mounted in top and bottom blocks 8 and 9 provided with tongues 10 whereby they are slidably mounted in the housing or frame 7, Fig. 3.

The spring motor preferably comprises a coil spring 11 surrounding a sleeve 12 and secured at its lower end to the block 9 and at its upper end to a driving or spinning member in the form of a bell pinion 13, 80 which may be attached to or formed integrally with the sleeve 12, and which is adapted to mesh with a pinion 2 formed on the axis of the rotor 1. For winding the spring prior to spinning, there is rotatably 85 mounted in the block 9 a shaft 14, provided with a wrench head 15, and having feathered thereto a pinion 16 adapted to mesh with a pinion 17 keyed to the sleeve. That the number of spring-winding turns 90 given to the sleeve 12 may be definitely limited, the shaft 14 has screw-threaded engagement with a frame 18 secured to the block 9, and the end of the shaft is provided with a nut or an equivalent adjustable but temporarily fixed stop 19, which, when the shaft has been given the required number of turns, is brought up against the top of the frame 18 and thereby prevents further turning of the shaft and consequent winding of the spring 11.

For locking the spring motor against unwinding, there is preferably secured to the mounting block 9 a spring pressed pawl 20 (Fig. 4) adapted to engage the pinion 17, 105 and provided with an arm 21. This arm is adapted to be moved, and through its movement the pawl tripped, by means of a plunger rod 22 mounted in a cylinder 23 and adapted to be moved outwardly by 110

means of compressed air or other motive fluid led to such cylinder through a pipe 24. The plunger 22 not only releases the pawl 20, but also, under the continued pressure of the air, moves outwardly from the cylinder and thereby holds the pawl released while the spinning mechanism moves laterally from the gyroscope in a manner presently to be explained.

10 While various instrumentalities may be provided for moving the spinning mechanism from the gyroscope upon the spinning thereof, I preferably provide spring impelled rack-and-pinion mechanism. In the 15 illustrative embodiment of this part of my invention, a shaft 25 is arranged within and co-axially with the sleeve 12 and is provided at its upper and lower ends with pinions 26 and 27, which mesh with racks 28 and 29 secured to the frame or support 7. This shaft is rotatably mounted in the slidable blocks 8 and 9. Surrounding the shaft there is a spring 30 secured at its opposite ends to sleeves 31 and 32, the former being keyed to 20 the shaft and the latter secured in any desired manner to the slidable mounting block 9. For simultaneously winding the spring 30 and moving the spinning mechanism to its operative position indicated in the drawings, the lower end of the shaft is provided 30 with a wrench head 33.

It will be understood that, when the spinning mechanism is in its operative position, the spring 30 will continually exert its tension upon the pinion shaft 25 and thus tend to cause such shaft to rotate and thereby move such mechanism from the gyroscope. To resist such functioning of the spring until the gyroscope has been spun, there is 40 provided a lock preferably in the form of spring-pressed bell crank levers 34, 35 pivotally mounted on the block 8, Fig. 2. The arms 34 of such levers are adapted to engage notches 36 formed in the supporting frame 35, and the arms 35 to be engaged by a tripping member or block 37 movable by the spinning mechanism. Preferably the tripping member is slidably mounted in the block 8 and is provided on its lower face 50 with suitable grooves adapted to receive a spiral thread 38 formed on the top of the bell 13. It will be understood that, prior to the spinning operation, this tripping member will be in a position to the right of that indicated in Fig. 1, and that the rotation of the bell 13 will cause such member to move toward and finally engage and trip the arms 35 of the bell crank levers, thereby releasing the spinning mechanism so that it may 60 move in response to the tension of the spring 30.

For stopping the movement from the gyroscope of the spinning mechanism, the upper end of the shaft 25 is preferably provided with a finger 45 (Fig. 2), which, as the

shaft rotates and moves laterally, engages a stop 46 secured to the frame 7. The relative positions of this finger and stop are such that they will arrest the lateral movement of the spinning mechanism or unit when such unit has, under the action of the spring 30, been moved clear of the range of movement of the gyroscope.

The apparatus also includes means for stopping the rotation of the spinning bell 75 after the mechanism, in its lateral movement from the gyroscope, has become disconnected from the gyroscope. For the purpose the periphery of the top horizontal portion of the bell 13 may, as shown in Fig. 2, be provided with a lug 42 adapted to strike against a depending abutment 43 formed on the sliding member 37. The arrangement and coordination of the parts are such that, during the rotation of the bell, the slide member 85 37 will first have been brought to such position as to trip the levers 35, 36 to cause the spinning mechanism to move laterally, and that thereafter the lug 42 will strike the abutment 43 to stop the rotation of the bell.

To lock the gyroscope prior to and during the spinning thereof, I preferably provide an arm 39 secured to a rotatably mounted shaft 40, which, in such manner as to hold the arm yieldingly toward the gyroscope, is acted upon by a spring 41. It will be seen that the upper end of the arm projects within the bell 13. As the spinning mechanism moves from the gyroscope the arm is engaged by the bell and moved from its gyroscope-locking position.

In describing the operation of my invention as illustrated herein, it will be assumed first that the spinning mechanism is in position to the right of that shown in Fig. 1, the spring motor being unwound. Preferably the first step in setting the mechanism is the winding of the spring 11. For this purpose the head 15 of shaft 14 is engaged by a suitable wrench and the shaft rotated until its stop 19 is brought up against the frame 18, it being understood that, prior to such winding, the shaft 14 is in a position above that indicated in Fig. 1. The driving connections for winding this spring include the pinions 16 and 17 and the sleeve 12, and the spring is locked in its normal position by means of the pawl 20, Fig. 4. During this winding of the spring 11 the tripping member 37 is, through the rotation of the bell 13, moved to the right of its indicated position thus releasing the levers 35, 36 so that they may properly function when the spinning mechanism is moved toward the gyroscope.

The next step in the setting of the spinning mechanism is the rotation of the shaft 25, whereby the spring 30 is wound, and, through pinions 26 and 27 and racks 28 and 29, the mechanism is moved toward the gy- 130

roscope until the teeth of the bell 13 are in a position to mesh with the pinion 2 of the rotor 1, at which position it will be held by the levers 34, 35 engaging the notches 36 of the frame. The gyroscope and locking arm 39 may then be manipulated to bring such parts into the positions indicated in Fig. 1.

The several parts being thus arranged and adjusted the spinning mechanism is released 10 by flow of pressure fluid to the cylinders 23 (Fig. 4), which moves the plunger 22 outwardly to trip the pawl 20, 21. The ensuing rotation of the bell 13 simultaneously spins the gyroscope and moves the tripping member 37 to the left, the arrangement being such that the tripping member will engage and trip the levers 34, 35 after a predetermined number of turns of the bell. This tripping of the levers permits the 20 spring 30 to exert its tension on the shaft 25 to cause it to rotate and thereby move the mechanism from the gyroscope, the rotation of the shaft being arrested by the finger 45 engaging the stop 46 after the mechanism 25 has moved far enough from the gyroscope to permit it to function freely, in its intended manner. The continued rotation of the bell 13 moves the tripping or slide member 37 farther to the left, thereby bringing its de- 30 pending abutment 43 in the path of the lug 42 formed on the bell, so that, when such lug strikes the abutment, the rotation of the bell will be stopped.

According to the provisions of the patent 35 statutes, I have described the principle and operation of my invention together with the construction which I now consider represents the best embodiment thereof. However, I desire to have it understood that my 40 invention may be practised by other forms of construction than that particularly shown and described.

I claim as my invention:

1. The combination with a gyroscope, of 45 spinning mechanism comprising a spring motor and a member secured thereto for making driving connections with said gyroscope, and means effective upon the spinning of the gyroscope to move said mechanism 50 including the spring motor from the gyroscope.

2. The combination with a gyroscope including a rotor provided with a spinning pinion, of spinning mechanism comprising 55 a spring motor and a bell-shaped gear secured thereto and adapted to mesh with said rotor pinion, and means effective upon the spinning of the gyroscope to move said mechanism from the gyroscope.

60 3. The combination with a gyroscope, of spinning mechanism comprising a spring motor and a rotary member secured thereto for making driving connections with the gyroscope, said mechanism being slidably 65 mounted to move laterally with respect to

the gyroscope, and means effective upon the spinning of the gyroscope to move said mechanism from the gyroscope.

4. The combination with a gyroscope, of spinning mechanism comprising a spring 70 motor and a member secured thereto for making driving connections with the gyroscope, means effective upon the spinning of the gyroscope to move said mechanism from the gyroscope, and means for moving said 75 mechanism in the opposite direction.

5. The combination with a gyroscope, of spinning mechanism comprising a spring motor and a member secured thereto for making driving connections with the gyroscope, a spring impelled mechanism for automatically moving said spinning mechanism 80 from the gyroscope upon the spinning thereof.

6. The combination with a gyroscope, of 85 spinning mechanism comprising a spring motor and a member secured thereto for making driving connections with the gyroscope, spring impelled mechanism for automatically moving said spinning mechanism 90 from the gyroscope, means for locking said moving mechanism, and means effective upon the spinning of the gyroscope for releasing said locking means.

7. The combination with a gyroscope, of 95 spinning mechanism comprising a spring motor and a member secured thereto for making driving connection with the gyroscope, spring impelled mechanism for moving said spinning mechanism from the gyro- 100 scope, a lock for restraining the operation of said moving mechanism and a movable member coöordinated with said spring mechanism for releasing said lock.

8. The combination with a gyroscope, of 105 spinning mechanism comprising a spring motor and a member secured thereto for making driving connections with the gyroscope, spring impelled mechanism for automatically moving said spinning mechanism 110 from the gyroscope, and manually operable means for moving said spinning mechanism in the opposite direction.

9. The combination with a gyroscope, of 115 spinning mechanism comprising a spring motor and a member secured thereto for making driving connections with the gyroscope, said mechanism being mounted to move laterally with respect to the gyroscope, and spring impelled rack-and-pinion 120 connections for effecting said movement of the spinning mechanism.

10. The combination with a gyroscope, of a spinning unit therefor, movable to and from spinning position; said unit comprising a spring motor, means for winding said motor, and spring impelled means effective upon the spinning operation of the spring motor for moving the unit from the gyro- 125 scope.

11. The combination with a gyroscope, of a spinning unit therefor slidably mounted for lateral movement to and from spinning position; said unit comprising a spring motor, spring impelled rack-and-pinion connections for moving said unit from the gyroscope, means for restraining said movement of the unit, and means effective upon the spinning operation of the spring motor for releasing said restraining means.
12. The combination with a gyroscope, of a spinning unit therefor slidably mounted for lateral movement to and from spinning position; said unit comprising a spring motor, spring impelled rack-and-pinion connections for moving said unit from the gyroscope, a releasable lock for restraining said movement of the unit, and a movable member coöordinated with said spring motor for releasing said lock.
13. The combination with a gyroscope, of a supporting frame, a block slidably mounted thereon, a shaft rotatably mounted in said block and provided with a pinion, a rack secured to said frame and meshing with said pinion, a spring motor gyroscope-spinning mechanism mounted on said shaft, and means for turning said shaft for moving said mechanism.
14. The combination with a gyroscope, of a supporting frame, a block slidably mounted thereon, a shaft rotatably mounted in said block and provided with a pinion, a rack secured to said frame and meshing with said pinion, a spring motor gyroscope-spinning mechanism mounted on said shaft, said pinion, a spring surrounding said shaft and exerting its tension thereon for the rotation thereof, a lever restraining the rotation of said shaft, a second spring surrounding said shaft, a bell-shaped gyroscope-spinning gear secured to said second spring, and a tripping member slidably mounted on said frame and having screw-thread engagement with said spinning gear, said member being adapted upon the rotation of the spinning gear to trip said lever.

In testimony whereof I have hereunto set my hand.

HAROLD W. SHONNARD.
